UNITED STATES PATENT OFFICE.

NELSON SHIELDS, OF MINNEAPOLIS, MINNESOTA.

HINGE.

1,051,166.

Specification of Letters Patent. Patented Jan. 21, 1913.

Application filed February 19, 1912. Serial No. 678,684.

To all whom it may concern:

Be it known that I, NELSON SHIELDS, a citizen of the United States, residing at Minneapolis, county of Hennepin, and State 5 of Minnesota, have invented certain new and useful Improvements in Hinges, of which the following is a specification.

My invention relates to grain doors and particularly to hinges adapted for use in 10 conjunction with the grain doors of cars.

The object of my present invention is to provide an improved grain door which shall be adapted to rest upon the floor or sill when closed and which cannot become jammed 15 when being opened, by particles becoming wedged between the lower edge of the door and the floor.

A further object of my invention is to provide improved hinge members for a 20 grain door which shall practically lock the door in both closed and open positions.

Other objects will appear hereinafter.

My invention consists generally in a grain door provided with the hinges hereinafter 25 fully described and in the various details of construction and arrangements as fully set forth in the claim.

My invention will be more readily understood by reference to the accompanying 30 drawings forming a part of this specification and in which—

Figure 1 is a detail longitudinal section of a grain car provided with a door equipped with a hinge embodying my invention, Fig. 2 is an enlarged elevation of the hinge mounting of the door with the parts in the position they assume when the door is closed, Fig. 3 is a similar view with the parts in the position they assume when 40 the door is fully open, and Fig. 4 is a horizontal section on the line $\alpha-\alpha$ of Fig. 2 and taken upon an enlarged scale.

Referring now to the drawings 1 indicates the side of a car having a door opening 2, 3 45 the roof and 4 the floor. The grain door 5 is illustrated in Fig. 1 as closing the lower portion of the door opening 2 in the usual manner, and resting upon the floor.

The door is hingedly connected to the side 50 of the car or suitable framing by hinges 6, and my invention is comprised in this hinge mounting of the door. Each hinge comprises a fixed leaf 7 adapted to be secured to the stationary portion of the structure and 55 a knuckle secured to or formed upon the

door 5. I prefer to form the door of sheet metal and form the knuckles 8 integral therewith by providing the door with lateral extensions or tongues 8', which are bent to form the knuckles as shown. The leaf 7 is 60 provided with a pair of spaced aligned pintle knuckles 9 and 10. These are spaced a considerable distance apart and secured in the same is a pintle 11, a rod forming a common pintle for all the hinges being preferably employed. The knuckles 8 on the door are of considerable less length than the distance between the adjacent ends of the knuckles 9 and 10 and are slidably mounted on the pintle between said knuckles. The 70 lowermost pintle knuckle, that is the knuckle 10, is enlarged in diameter and provided with an upwardly extending portion 13, which is of segmental cylindrical form and hollow whereby the knuckle 8 may freely 75 pass within the same to engage or rest upon the knuckle 10. The upper edge 14 terminates at a distance below the lower end of the knuckle 9 slightly greater than the length of the knuckle 8 for a purpose which 80 will appear hereinafter. The outer edge 15 of the extension or portion 13 terminates substantially in a plane with the inner face of the door 5 when said door is in closed position, by which arrangement said extension 85 practically locks the door when in closed position by the edge 15 abutting the adjacent portion of the inner face of the door or that of the tongues 8' as shown in Figs. 2 and 4. The inner edge 16 of said extension terminates 90 in a plane substantially parallel with the inner face of the leaf 7 and spaced therefrom a distance slightly greater than the thickness of the door 5 whereby the adjacent portion of said door or the tongues 8' is received between the leaf 7 and the edge 16 95 when the door is in open position to substantially lock the door against closing.

To open the door it is raised until the knuckle 8 engages the knuckle 9 and then pushed inwardly, the adjacent portion of the tongues 8' resting upon the edge 14 of the extension 13. This holds the door out of engagement with the floor while being opened thereby preventing the same from 100 becoming jammed. As soon as the door reaches fully opened position the tongue 8' will drop into the space behind the member 13 and the door cannot be again closed until it is raised.

Having described my invention what I claim as new and desire to secure by Letters Patent is:—

A hinge comprising a fixed leaf and a swinging portion, a pair of spaced alined knuckles on said fixed leaf, a pintle supported in said knuckles, a knuckle on said swinging portion of less length than the distance between the first said knuckles and 10 slidably mounted on said pintle, a segmental hollow cylindrical extension projecting upwardly from the lowermost knuckle on the fixed leaf, the inner edge of said extension

being provided with a notch adjacent said fixed leaf forming a vertical edge and the 15 outer edge thereof being vertical and adapted to abut the swinging portion when in closed position, said notch being of less depth than said vertical outer edge.

In testimony whereof I have signed my 20 name to this specification in the presence of two subscribing witnesses.

NELSON SHIELDS.
